UNITED STATES PATENT OFFICE.

THOMAS BAIRD ANDERSON, OF COSHOCOTON, OHIO.

DESIGN FOR A CASSEROLE.

Application filed July 17, 1925. Serial No. 14,125. Term of patent 7 years.

To all whom it may concern:

Be it known that I, THOMAS B. ANDERSON, a citizen of the United States, residing at Coshocton, in the county of Coshocton and State of Ohio, have invented a new, original, and ornamental Design for Casseroles, of which the following is a specification, reference being had to the accompanying drawing, forming part thereof.

I claim:

The ornamental design for a casserole, as shown.

THOMAS BAIRD ANDERSON.
